(57) **CLAIM**

The ornamental design for a LED lighting tube, as shown and described herein.

DESCRIPTION

FIG. 1 is a perspective view of a first embodiment of the LED lighting tube.

FIG. 2 is a front view of the LED lighting tube shown in FIG. 1.

FIG. 3 is a right side elevational view of the LED lighting tube shown in FIG. 1.

FIG. 4 is a rear view of the LED lighting tube shown in FIG. 1.

FIG. 5 is a left side elevational view of the LED lighting tube shown in FIG. 1.

FIG. 6 is a top view of the LED lighting tube shown in FIG. 1.

FIG. 7 is a bottom view of the LED lighting tube shown in FIG. 1; and,

FIG. 8 is a perspective view of a second embodiment of the LED lighting tube, with the tube partitioned to indicate that the LED lighting tube may be any length.

The broken line portions of the disclosure are for illustrative purposes only and form no part of the claimed design.

1 Claim, 5 Drawing Sheets
